UNITED STATES PATENT OFFICE.

FREDERICK W. OPEL AND JOHN G. OPEL, OF IRELAND, INDIANA, ASSIGNEES OF ONE-THIRD TO HOMER WINEINGER, OF IRELAND, INDIANA.

WIRE FENCE.

SPECIFICATION forming part of Letters Patent No. 700,074, dated May 13, 1902.

Application filed November 20, 1901. Serial No. 83,050. (No model.)

To all whom it may concern:

Be it known that we, FREDERICK W. OPEL and JOHN G. OPEL, citizens of the United States, residing at Ireland, in the county of Dubois and State of Indiana, have invented a new and useful Wire Fence, of which the following is a specification.

Our invention relates to an improvement in wire fences, one object of our invention being to provide an improved post, which is not buried in the ground, but is supported upon a permanent base, and which post when it becomes decayed or broken may be removed without taking down the fence-wires and replaced by another.

A further object of our invention is to provide improved means for bracing the post and for preventing the top fence-wire from sagging.

With these and other objects in view our invention consists in the peculiar construction and combination of devices hereinafter fully set forth and claimed.

In the accompanying drawings, Figure 1 is a perspective view of a section of a wire fence embodying our improvements. Fig. 2 is a detail sectional view taken transversely through the upper portion of one of the posts, showing the bight of the brace-wire, the top fence-wire, and the hook which suspends the bight of the brace-wire from the said top wire. Fig. 3 is a similar view showing the operation of the device we employ and have devised for tightening the brace-wire. Fig. 4 is a similar view on a plane at right angles to that of Fig. 3. Fig. 5 is a detail sectional view showing the modified form of the hook for suspending the brace-wire from the top wire.

In the embodiment of our invention we provide a permanent base 1 for each of the posts 2. The base 1 may be a boulder partially buried in the ground or it may be a brick or stone pier, and we do not limit ourselves in this particular. On opposite sides of the brace 1 are buried anchors 3, which may be stones, bricks, or other suitable objects. The post 2 is provided on its upper end with a transverse vertical slot 4 of suitable length, and the post is provided at its upper and lower ends with notches 5 6 for the reception and retention, respectively, of the top and bottom wires *a b* of

the fence. The top wire is supported at two points by the post, on opposite sides of the slot 4. A brace-wire 7 of suitable size and length has its ends connected to the anchors 3 and 55 its bight disposed in the slot 4 in the upper end of the fence-post. A hook 8 engages the bight of the brace-wire and also engages the top wire *a* of the fence, and the stress of the brace-wire is thus communicated to the top 60 wire, so that the weight of the wire fabric of the fence operates to maintain the tension on the brace-wires, and the latter act to prevent the fence-wires from sagging in addition to performing their function of bracing the posts 65 and maintaining the latter in their vertical position. A loop 8^a, which is disposed in a transverse opening 9 in the post, may be employed to draw the brace-wires to the post and prevent the brace-wires from forming ob- 70 structions; but the use of the said loop may be dispensed with without affecting the scope or impairing the advantages of our invention.

In the erection of the fence we employ a device (shown in Figs. 3 and 4) for tightening 75 the brace-wires prior to connecting them by means of the hook 8 to the top wire. The said tightening device comprises an arched support 10, which is adapted to be placed on the top of the post and to span the slot 4 thereof, 80 a screw 11, which operates vertically in an unthreaded opening in the said arched support 10 and is provided with a hook 12 at its lower end to engage the bight of the brace-wire, and a nut 13, which coacts with the screw to elevate the latter, bears on the arched support 10 and is provided with a lever-arm 14 to enable it to be turned.

Instead of forming the hook 8 from a piece of wire, as hereinbefore stated, the same may 90 be of the form shown in Fig. 5, provided on one side with a series of notches 15, adapted to engage the top wire *a*, hence enabling the said hook to be adjustably connected to the top wire. 95

Having thus described our invention, we claim—

1. In a fence, the combination of a post, a fence-wire supported thereby, at two points, and a brace connected to the said fence-wire, 100 between said supported points thereof, said wire and brace each maintaining the tension

of the other, and whereby the sagging of the wire between two posts adds tension to the brace, substantially as described.

2. In a fence, the combination of a post, a fence-wire supported thereby at two points, a brace for the post, and an adjustable connection between the said brace and the said wire, said connection being attached to the wire between the supported points thereof, said wire and brace each maintaining the tension of the other, substantially as described.

3. In a fence, the combination of a post having a transverse slot, a fence-wire supported by the post, a brace having a bight disposed 15 in the said slot, the said brace being connected to and supported by the said wire, substantially as described.

4. In a fence, the combination of a base, a post supported on and detachable from the 20 base, a fence-wire supported by the post at two points, and a brace-wire transversely disposed with reference to the post, the bight of said brace-wire being connected to said fence-wire between the supported points thereof, 25 said fence-wire contributing to the tension of said brace-wire, substantially as described.

5. In a fence, the combination of a base, a post supported on and detachable from the base, a wire fabric having its upper and lower

wires engaged with the upper and lower ends 30 of the post and its intermediate wires bearing against one side of the post, and a brace for the latter, substantially as described.

6. In a fence, the combination of a base, a post supported on and detachable from the 35 base, a wire fabric having its upper and lower wires engaged with the upper and lower ends of the post and its intermediate wires bearing against one side of the post, and a brace for and detachable from the latter, substantially as described.

7. In a fence, the combination of a base, a post supported on and detachable from the 40 base, a wire fabric having its upper and lower wires engaged with the upper and lower ends 45 of the post and its intermediate wires bearing against one side of the post and a brace for the post, detachably connected to said upper wire, substantially as described.

In testimony that we claim the foregoing as 50 our own we have hereto affixed our signatures in the presence of two witnesses.

FRED. W. OPEL.

JOHN G. OPEL.
